UNITED STATES PATENT OFFICE.

AUGUSTE LAFOURCADE, OF NEW YORK, N. Y.

COMBINATION LAUNDRY-TABLE.

1,197,501.

Specification of Letters Patent. Patented Sept. 5, 1916.

Application filed November 27, 1915. Serial No. 63,782.

To all whom it may concern:

Be it known that I, AUGUSTE LAFOURCADE, a citizen of France, residing at New York, in the county of New York and State of New York, have invented new and useful Improvements in Combination Laundry-Tables, of which the following is a specification.

This invention relates to laundry apparatus and has for its principal object the provision of a structure of this character which may be instantly converted from an article of one design and for a particular purpose to an article of another design for a different purpose and one which may be made to occupy little floor space while in use.

A further object of the invention resides in the provision of a device of this character which will include a drying and draining frame, a drip tray and a washing tub, the latter being adjustably mounted beneath the former and adapted to be associated or related thereto whereby to permit the clothes as they are taken from the tub to be placed upon the frame at the convenience of the user.

In the drawings forming a part of this specification and in which like reference numerals indicate similar parts throughout the several views: Figure 1 is a perspective view of the structure showing the table top removed and the tub extended from one side of the stand. Fig. 2 is a vertical section therethrough showing the table top in its normal position. Fig. 3 is a perspective view of the table top. Fig. 4 is a sectional perspective view of a portion of the tub showing the locking means therefor.

With a view to providing a combination laundry structure which will be simple, strong, durable and inexpensive and one which includes several useful sub-structures, convertible from one to another at the convenience of the user and also a device which will occupy but comparatively little floor space, use is made of a stand 1 consisting of vertical legs 2, a lower frame 3 and a top frame 4. The legs 2 extend above the top frame 4 and as illustrated in Fig. 2, they

are adapted to be inserted in sockets 5 in a top 6, the latter being formed of porcelain or other suitable well known material, and said top is designed to normally over-lie the super-structure of the device and partly conceal the same and thereby add to the general attractiveness of the device. 55

Slidably mounted upon the lower frame 3 is a tub 7 having a pair of legs 8-8 which are adapted to support the same in an operative position as shown in Fig. 1. At the opposite end the said tub is provided with stop plates 9-9 having keeper passages 10 therein to receive the lower ends 11 of sliding keeper plates 12. These keeper plates 65 are supported from the adjacent legs 2 of the device and when adjusted so as to cause said ends 11 to extend through the passages 10, it is seen that the tub will be effectually held against sliding movement. The adjustment of the tub to an extended position is limited through the fact that the plates 9 come in contact with the mentioned adjacent legs 2. 70

A drain tray 13 is mounted upon the upper frame 4, being provided with a bottom 14, sides 15-15, an end wall 16 and a mouth shaped discharge end 17. The bottom 14 is inclined in the direction of the mouth 17 and the latter opens directly into the tub 7 80 when said tub is extended to the position illustrated in Fig. 1. A horizontally disposed reticulated member or clothes support 18 is removably mounted upon the drain tray and the same is adapted to hold the 85 clothes spaced from the bottom of said tray whereby to permit of a thorough draining of the clothes as they are conducted from the tub. By spacing the support 18 from the bottom of the drain tray, provision is 90 made for air entering under the support which will tend to effect a drying of the clothes during the draining thereof.

When the tub is not in use, it may be extended under the frame 4 and the top 6 95 then placed in position upon the extended upper ends of the legs 2 and the device, as a whole made to assume a comparatively compact and neat package as will be observed. The bottom of the tub may be pro- 100

vided with a drain tube 20 and a removable plug 21 of usual pattern and as indicated in Fig. 2.

What is claimed as new is:—

- 5 A laundry apparatus comprising a stand, a drain tray mounted thereon, a tub mov-
ably mounted on the stand, stops carried by
the tub and engageable with the stand to
limit the movement of the tub, and keepers

movably mounted on the stand and engage- 10
able with the stops to fix the tub with rela-
tion to the stand.

In testimony whereof I affix my signature
in presence of two witnesses.

AUGUSTE LAFOURCADE.

Witnesses:

ANNA V. DOYLE,
GEO. A. BYRNE.
